DESIGN FOR A LIP STICK SAMPLER OR THE LIKE

Robert T. Christy, New York, N. Y.

Application June 18, 1934, Serial No. 52,226

Term of patent 14 years

To all whom it may concern:

Be it known that I, Robert T. Christy, a citizen of the United States of America, and resident of New York city, county and State of New York, have invented a new, original, and ornamental Design for Lip Stick Sampler or the like, of which the following is a specification, reference being had to the accompanying drawing, forming part hereof.

In the drawing:

I claim:

The ornamental design for a lip stick sampler or the like substantially as shown.

ROBERT T. CHRISTY.
